UNITED STATES PATENT OFFICE

163,826

WATER PITCHER

Louis M. Schnitzer, Brooklyn, N. Y., assignor to
Everlast Metal Products Corp., a corporation
of New York

Application November 21, 1949, Serial No. 6,170

Term of patent 14 years

(Cl. D44—21)

To all whom it may concern:

Be it known that I, Louis M. Schnitzer, a citizen of the United States, residing at Brooklyn, in the county of Kings, State of New York, have invented a new, original, and ornamental Design for a Water Pitcher, of which the following is a specification, reference being had to the accompanying drawing, forming part thereof.

Fig. 1 is a side perspective view of a water pitcher, showing my new design; and

Figs. 2 and 3 are respectively front and rear perspective views thereof.

I claim:

The ornamental design for a water pitcher, as shown.

LOUIS M. SCHNITZER.
